LEER

Original Filed Oct. 24, 1927

UNITED STATES PATENT OFFICE

RICHARD LA FRANCE, OF TOLEDO, OHIO, ASSIGNOR TO OWENS-ILLINOIS GLASS COMPANY, OF TOLEDO, OHIO, A CORPORATION OF OHIO

LEER.

Application filed October 24, 1927, Serial No. 228,145. Renewed March 29, 1930.

The present invention relates to improvements in means for annealing glassware or the like articles, and particularly to that type in which an endless chain conveyor is utilized 5 to carry ware through a leer tunnel. More particularly, the invention relates to leers of the muffle type in which the ware is annealed by radiation of heat so that the ware is kept out of contact with products of combustion, 10 the latter being conducted through a flue and exhausted to the atmosphere.

In leers of the muffle type, the products of combustion are exhausted to the atmosphere, thereby wasting considerable heat which, according to the present invention, is utilized in 15 preheating the leer pans to a degree substantially corresponding to that of the ware being annealed. Thus, the pans are prevented from absorbing heat from the bottoms of the 20 ware, which quite obviously contributes to the elimination of strains in the annealed glass. Ordinarily, the pans upon reaching the ware receiving station, are either comparatively cold or have been preheated by using 25 a separate burner designed and installed for the sole purpose of heating the pans. According to the present invention the necessity for employing this separate burner is eliminated and the products of combustion are 30 caused to follow a path in which they come in direct contact with and effectually heat the leer pans just before the latter reach the ware receiving station. Thus, the expense of installation and maintenance of a special burner 35 is eliminated and a medium heretofore wasted is utilized to perform an important function.

Other objects will be apparent hereinafter. In the accompanying drawings:

Fig. 1 is a vertical central longitudinal sectional view of a portion of a leer constructed in accordance with the present invention.

Fig. 2 is a sectional view along the line II-II of Fig. 1.

The leer comprises side walls 5 and a cover 45 or ceiling 6 formed of suitable insulating material supported on a frame 7 which may comprise a plurality of transverse I-beams 8 interconnecting the upper ends of columns 9 formed of channel iron or the like. These 50 frame units are preferably supported on lon-

itudinal channel irons 10 serving as base members for the framework and held against outward movement by uprights 11 which are rigidly fixed to the floor 12 and suitably interconnected at their upper ends.

An endless ware conveyor 15 comprising a series of interconnected transverse pans, runs over sprockets 16 which in part space the upper and lower reaches 17 and 18 of the conveyor as illustrated in Fig. 1. The upper 60 reach of the conveyor is spaced below the ceiling 6 and runs over a series of anti-friction rollers 30 (Fig. 2) to thereby facilitate movement of the loaded conveyor through the leer tunnel. These rollers 30 are journaled 65 in angle irons 19 resting upon the leer floor 20 forming the upper wall of a flue 21 which extends longitudinally of the leer to conduct products of combustion from the heating unit 22 rearwardly a predetermined distance. 70

The flue 21 at the inner end of the heating zone is directed downwardly and then forwardly to a point in proximity to the heating unit 22 where it opens into a chamber 26 communicating with the open forward end of an 75 exhaust flue 23 which accommodates the forwardly moving reach of the ware conveyor 15. The lower wall 24 of the lower branch of the flue 21 forms the upper wall of the exhaust flue 23 through which the conveyor 80 extends and by way of which the products of combustion are conducted rearwardly to a point at which they are exhausted to the atmosphere through a stack (not shown). The lower reach 18 of the ware conveyor 15 85 (Fig. 2) moves over a series of anti-friction rollers 25 which space the former from the bottom 12 of the leer.

Ware passing through the heating zone is brought to, or maintained at, the proper temperature by heat radiated from the floor 20 of the tunnel. After passing beyond this heating zone, the ware is gradually cooled by any preferred means. Products of combustion passing through and from the flue 21 first 90 contact with the lower reach of leer pans at a point adjacent the heating unit 22, bringing such pans to substantially the desired temperature just prior to placing ware on said pans. The intense heat of the products of 95 100

combustion at the time they enter the exhaust flue 23, serves as an exceptionally effective preheating means for the pans. As the products of combustion move rearwardly through the exhaust flue 23, the heat is more or less dissipated and quite obviously the temperature of the pans decreases rearwardly through the flue 23. This condition is of considerable advantage in that the pans are gradually brought to the proper temperature as they approach the forward end of the leer and are not brought from a relatively cold area and suddenly subjected to heating by an intense flame. Accordingly, it is evident that the life of the conveyor is thereby prolonged.

Modifications may be resorted to within the spirit and scope of the appended claims.

What I claim is:

1. A glassware annealing leer comprising a ware receiving tunnel having an imperforate floor, an endless conveyor having one reach running over the floor of the tunnel and another reach spaced therebelow, a heating unit at the forward end of the leer, means to conduct products of combustion along and in contact with the lower side of the tunnel floor to heat said tunnel by radiation, and means to then direct the products of combustion into contact with the lower reach of the conveyor.

2. A glassware annealing leer comprising a ware receiving tunnel having an imperforate floor, an endless conveyor having one reach running over the floor of the tunnel and another reach spaced therebelow, a heating unit at the forward end of the leer, means to conduct products of combustion along and in contact with the lower side of the tunnel floor to heat said tunnel by radiation, means to then direct the products of combustion into contact with the lower reach of the conveyor, and means whereby the products of combustion are so applied to the lower reach of the conveyor that the temperature of the latter is gradually increased as it moves forwardly.

3. A glassware annealing leer comprising a ware receiving tunnel having an imperforate floor, an endless ware conveyor having one reach running through the tunnel and another reach spaced therebelow, an exhaust flue enclosing a major portion of the lower reach of the conveyor and open at its forward end, means to conduct products of combustion along and in contact with the lower side of the tunnel floor to heat the tunnel by radiation, and means to then conduct the products of combustion to and into the open end of said exhaust flue to heat the lower reach of the conveyor.

4. A glassware annealing leer comprising a ware receiving tunnel having an imperforate floor, an endless ware conveyor having one reach running through the tunnel and another reach spaced therebelow, an exhaust flue enclosing a major portion of the lower

reach of the conveyor and open at its forward end, a heating unit arranged at the forward end of the leer, a flue communicating with said heating unit and extending longitudinally of the leer to conduct products of combustion along and in direct contact with the lower side of the tunnel floor, and a forwardly extending flue arranged to conduct the products of combustion to the open front end of the exhaust flue.

5. A glassware annealing leer comprising a ware receiving tunnel having an imperforate floor, an endless ware conveyor, a heating unit arranged to heat at least a portion of the tunnel by radiation, and means to conduct products of combustion from the heating unit into direct contact with a portion of the conveyor to heat the latter prior to entry into said tunnel.

6. A glassware annealing leer comprising an annealing compartment having an imperforate floor, a ware conveyor running through said compartment, means for supplying hot gases of combustion, a channel through which said gases are conveyed, said channel comprising a portion extending along the said conveyor and supplying radiated heat from said gases to the annealing compartment while maintaining said gases out of contact with the ware in said compartment, and means for bringing said gases into direct contact with a portion of the conveyor moving toward said annealing compartment and thereby heating said portion of the conveyor.

7. In a glassware annealing leer, the combination of an annealing compartment having an imperforate floor, a ware-carrying conveyor running through said compartment, means for supplying gases of combustion and heating said annealing compartment by heat radiated from said gases while maintaining the gases out of contact with the ware in said compartment, and means for bringing said gases into direct contact with the conveyor and thereby heating the latter prior to its entry into the annealing compartment.

Signed at Toledo, in the county of Lucas and State of Ohio, this 22nd day of October, 1927.

RICHARD LA FRANCE.
